MAURICE F. BEETHAM, OF HARVEY, ILLINOIS, ASSIGNOR TO WHITING CORPORATION,
OF HARVEY, ILLINOIS, A CORPORATION OF ILLINOIS

CHARGING APPARATUS FOR CUPOLAS

Application filed October 23, 1926. Serial No. 143,572.

The invention relates to charging apparatus for cupolas.

In placing charges of iron and coke into the cupolas, it is desirable to distribute the material uniformly over the bed, and one object of the invention is to provide a simple and efficient device for effecting such distribution which is movable into and out of the cupola.

Another object of the invention is to provide improved means for preventing disintegration of the wall or lining of the cupola by the material discharged into it.

Another object is to provide easily operable means for dumping charges of material into the cupola.

Other objects of the invention will appear from the following detailed description.

The invention consists in the several novel features hereinafter set forth and more particularly defined by the claims at the conclusion hereof.

In the drawings: Fig. 1 is a vertical section of a cupola to which the invention is applied, the distributor being illustrated in its operative position. Fig. 2 is a similar view, the distributor being shown in its inoperative position. Fig. 3 is a horizontal section. Fig. 4 is a section taken on line 4-4 of Fig. 1, the dump car being omitted. Fig. 5 is a horizontal section through the fulcrum for the beam which carries the distributor. Fig. 6 is a section taken on line 6-6 of Fig. 3. Fig. 7 is a detail of one of the adjustable fulcrum-plates on the beam.

The invention is exemplified with apparatus comprising a cupola A extending vertically through a horizontal charging-floor B, as well understood in the art, and provided with a charging opening a formed in a metal door-frame a' adjacent the level of the charging-floor. The charging floor consists of the usual boards b¹¹ supported on I-beam girders b⁶ and a metal plate b¹⁰ over the boards and adjacent the opening a. A dump-car C, adapted to travel on the charging floor, is constructed so that one end is adapted to project through the charging opening a a sufficient distance to dump the material into the cupola. This car has a pair

of wheels c' which are disposed adjacent the longitudinal center of the car, so that the load will be approximately balanced on said wheels and so the car-body may swing about the axis of said wheels. In dumping, the car-body c fulcrums on the axle of the wheels c'. A second pair of wheels c² is provided adjacent the rear of the car, so that it may be easily wheeled around on the charging floor with or without a load of material in the body. Legs c⁴ are fixed to, and depend from, the forward end of the car-body and clear the floor when both pair of wheels contact with the charging floor. When the car is in dumping position, as shown in Fig. 1, the legs are suspended in the cupola, and when the car is on the charging floor, these legs limit the vertical tilting of the car to prevent the load from being spilled. The car-wheels c' are directed by relatively flared guide-bars b to bring the car-body into correct position to enter the charging opening, and abutments b' are adapted to receive the wheels c' to stop the car at the correct point for dumping and to hold the wheels while the body is lifted to dump its contents into the cupola.

This construction exemplifies an approximately balanced dump-car which will be readily guided into, and retained in, its correct position for dumping the loads in a predetermined direction in the cupola, so that the material will be uniformly distributed by the distributor hereinafter set forth. The opening a is adapted to be closed by a door comprising an angle-iron top bar a² and a series of suspended chains a³. The cross-bar a² is vertically slidable in ways a⁴ so that it may be lifted by a suitable suspension device a⁵ to raise the chains a³ above the charging opening a.

The improved distributor for the material discharged from the car C comprises a head d having its upper face convex or hemispherical to cause the material dumped from the car to be deflected uniformly throughout the cupola, and a tilting beam d', one end of which carries the head d. This beam is centrally fulcrumed on a pin d² and provided at its opposite end with a counterweight d³.

The fulcrum-pin d^2 is disposed so that the distributor-head d may swing into operative position in the center of the cupola (Fig. 1) and into a vertical or inoperative position (Fig. 2), so that by swinging said beam, the distributor may be rendered operative during the charging and readily withdrawn from the cupola toward the end of the heat and after the last charge has been delivered to and distributed in the cupola. The beam d' is I-shaped in cross-section and its fulcrum-pin d^2 is supported by the bracket-plates d^{30} which are fixed to vertical angle-iron bars d^4 which are fixed to the cupola wall and the door-frame a' . Beam d' is confined transversely between the plates d^{30} so it will swing vertically only. The beam moves through a slot b^3 formed in the charging floor B adjacent the cupola when the distributor beam is in its inoperative position. Adjacent said slot, the charging floor is supported by a frame-work consisting of an I-shaped beam b^4 which extends under the floor and is fixed to the girders b^5 on which the floor B is superposed, I-beam sections b^6 at the sides of slot b^3 , each having one end fixed to beam b^4 and its other end to one of a pair of channel beams b^7 which are fixed to the girders b^5 .

The counter-weight d^8 preferably consists of a series of plates or sections which are removably secured to the beam by bolts d^{31} so that the effective weight may be varied to afford the desired assistance to the operator in shifting the beam, which is usually done by inserting a hook on a suitable rod through the charging opening and lifting the inner end of the beam d' . When the beam is in its inoperative position, shown in Fig. 2, the counterweight will hold it against displacement.

In some instances, it is also desirable to adjust the position of the distributor head relatively to the fulcrum d^2 of the beam d' by adjusting the beam. For this purpose, the web of the beam d' is provided with an elongated slot d^{12} through which the pin d^2 passes and with series of holes d^9 . Bolts d^{10} are adapted to pass through said holes and to clamp reinforcing plates d^{11} to said web. By removing the bolts d^{10} , the beam may be adjusted longitudinally to bring the distributor into the desired position in the cupola. The head d is composed of an upper convex section d^{13} which fits over and projects laterally from the flanges of beam d' and a pair of lower sections d^{14} which fit against and are secured to the web of the beam by bolts d^{15} . Bolts d^{16} , with countersunk heads, secure the upper and lower sections together. An arched plate d^{17} is secured to the top of the beam adjacent the head to deflect the material from, and to protect the beam. A lug d^{18} is secured to the beam d' to stop the car at a uniform angle or position in dumping.

In the discharging of iron from dump cars,

the distributor deflects the metal so it will be impacted against the cupola wall of refractory material. To prevent disintegration of the wall, the cupola is lined with an annulus H of metal which consists preferably of a series of arcuate hollow blocks h set into the refractory material of the wall of the cupola. This annulus is extended vertically throughout the area adjacent the distributor where the material is impacted against the wall.

The operation of the apparatus will be as follows: Normally, when the cupola is in operation and has been charged, the door a^2 will be closed and the beam d' will be in its vertical position illustrated in Fig. 2. When charges of iron or coke are to be delivered into the cupola, the door is lifted and the beam d' is swung into its horizontal position to bring the distributor-head into its operative position in the cupola. The car of material will then be run against the abutments b' and tilted until it strikes stop d^{18} so it will dump the material therein at a definite or predetermined direction, as illustrated in Fig. 1. The material discharged will be directed onto the top of the distributor d and the deflector plate d^{17} and thereby deflected into substantially all direction so that the material, when it falls on the bed in the cupola, will be substantially uniformly distributed throughout. After the cupola has been charged and more particularly toward the end of a heat, the beam d' will be swung into its vertical and inoperative position, as shown in Fig. 2, so the distributor will not be melted. During the charging of iron, the metal lining H will relieve most of the impact and thus protect the refractory wall of the cupola.

The invention exemplifies charging apparatus for cupolas which is adapted to be readily moved into and out of the cupola for speedy operation in connection with charging; in which a tilting beam is utilized to swing the distributor-head into and out of the cupola; which may be readily adapted to cupolas of usual construction; which comprises a readily operable dump-car for discharging loads into the cupola from a charging floor; and in which provision is made for preventing the disintegration of the refractory material by impact from the material dumped into the cupola.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In combination with a cupola provided with a charging opening, a distributor comprising a beam movably supported by the cupola, and a head on the beam for distribut-

ing material into the cupola as it is discharged through the opening.

2. In combination with a cupola provided with a charging opening, and a charging floor adjacent the opening on which a dump car may be operated to discharge material through the opening, a distributor for the material mounted on the cupola and movable through said opening into and out of the cupola.

3. The combination with a cupola provided with a charging opening, of a distributor for material delivered into the cupola through the opening, a vertically tilting beam by which the distributor is carried, movable to swing the distributor into and out of the cupola, and means to adjust the beam to vary the position of the distributor in the cupola.

4. The combination with a cupola provided with a charging opening, of a distributor for material delivered into the cupola through the opening, and a medially pivoted beam on one end of which the distributor is carried, said beam being arranged so that the distributor may be swung into and out of the cupola, the other end of the beam being counterweighted.

5. The combination with a cupola provided with a charging opening, and a charging floor adjacent the opening on which a dump-car may be operated to discharge material through the opening into the cupola, of a distributor for the material, and a beam fulcrumed under the floor and carrying the distributor, said beam being arranged so that the distributor may be swung into and out of the cupola, the floor being provided with a slot through which one end of the beam may swing.

6. The combination with a cupola provided with a charging opening, and a charging floor adjacent the opening on which a dump-car may be operated to discharge material through the opening into the cupola, of a distributor for the material, a beam carrying the distributor, and a fulcrum whereby the beam is supported so that the distributor may be swung into and out of the cupola, said fulcrum being mounted on the cupola structure.

7. The combination with a cupola provided with a charging opening at one side thereof, and means for delivering charges of material into the cupola through said opening, of a distributor-member supported independently of the delivery means and adapted to distribute the material in the cupola as it is discharged through the opening, and means for adjusting the distributor-member laterally with respect to the cupola.

8. The combination with a cupola provided with a charging opening, of a pivoted beam, a head mounted on one end of the beam and adapted to distribute in the cupola material discharged through the opening, and means to adjust the beam-pivot to vary the

position of the head when it is in the cupola.

9. The combination with a cupola provided with a charging opening, and a charging floor adjacent the opening on which a dump car may be operated to discharge material through the opening, of means to stop the car in a predetermined dumping position, and a distributor for the material movable into and out of the cupola and on which the stop is mounted.

10. The combination with a cupola provided with a charging opening, of a distributor for material charged into the cupola through the opening, and a beam by which the distributor is carried, the distributor being formed of separate sections and secured directly to the beam.

11. The combination with a cupola provided with an opening in one side thereof, of means for distributing the material discharged into the cupola, and a member to which the distributing means is secured, said member being mounted pivotally and arranged so that said means may be swung into and out of the cupola through said opening.

12. The combination with a cupola provided with an opening in one side thereof, of means for distributing the material discharged into the cupola, and a vertically tilttable member to one end of which the distributing means is secured, said member being arranged so that said means may be swung vertically into and out of the cupola through said opening.

13. The combination with a cupola provided with a charging opening, of means for distributing the material discharged into the cupola through said charging opening, and a vertically tilting member to one end of which the distributing means is secured, said member being supported by the cupola and arranged so that said means may be swung vertically into and out of the cupola through the charging opening.

14. In combination with a cupola provided with a charging opening, a distributor comprising a beam and a head fixedly secured to one end of the beam, said beam being mounted on the cupola and adapted to support the head so that it is disposed centrally in the cupola and operates to distribute uniformly and evenly the material discharged through the charging opening.

15. In combination with a cupola provided with a charging opening, a distributor for distributing uniformly and evenly in the cupola the material discharged through the charging opening, said distributor comprising a beam supported by the cupola and a head secured directly and fixedly to one end of the beam.

16. In combination with a cupola provided with a charging opening, and means for delivering charges of material into the cupola through said opening, of a distributor-head against which is impacted the material dis-

charged from said delivery means through the charging opening, and means supported independently of said delivery means and by the cupola for supporting the distributor-head so that it is movable from an operative position in the cupola to an inoperative position outside of the cupola.

17. The combination with a cupola provided with a charging opening in one side thereof and means for delivering charges of material into the cupola through said opening, of a distributor-head against which is impacted the material discharged from said delivery means through said charging opening, and a mount whereby said distributor-head is supported so that it is movable through the charging opening from its operative position in the cupola into an inoperative position outside of said cupola.

18. The combination with a cupola provided with a charging opening and means for delivering charges of material into the cupola through said opening, of a distributor-head against which is impacted the material discharged from the delivery means, and a supporting-member for the distributor-head, said member being mounted pivotally on the cupola structure and arranged so that said head may be swung vertically through the charging opening from its operative position in the cupola to an inoperative position outside of the cupola.

19. The combination with a cupola provided with a charging opening and a charging floor adjacent the opening on which a dump car may be operated to discharge material through the opening, of means for distributing in the cupola the material dumped from the car through the charging opening, and means supported beneath the level of the charging floor whereby the distributing means may be moved into and out of the cupola.

Signed at Harvey, Illinois, this 23rd day of Sept., 1926.

MAURICE F. BEETHAM.
